UNITED STATES PATENT OFFICE.

MILTON GOODMAN, OF NEW YORK, N. Y.

VACUUM CLEANER.

Application filed April 25, 1924. Serial No. 709,010.

To all whom it may concern:

Be it known that I, MILTON GOODMAN, a citizen of the United States, and a resident of the city of New York, borough of Manhattan, in the county and State of New York, have invented a new and Improved Vacuum Cleaner, of which the following is a full, clear, and exact description.

This invention has relation to vacuum cleaners and refers more particularly to an improvement in the same whereby to increase the efficiency thereof.

In the present construction of vacuum cleaners now in general use, it has been observed that the continuous flow of the suction draft through the intake mouth of the suction nozzle does not as effectually lift and remove the dust, dirt or other foreign matter from the surface being cleaned as where the suction draft is interrupted so that the surface being cleaned is subjected to intermittent puffs of suction draft.

It is, therefore, the outstanding object of the present invention to associate with a vacuum cleaner, a means for periodically or intermittently interrupting the suction draft through the intake mouth of the suction nozzle for the above mentioned purpose.

As a further object the invention contemplates in connection with a vacuum cleaner which includes a suction nozzle having an intake mouth and a chamber communicating with the opposite end of the suction nozzle provided with means for expelling the air therefrom for creating a partial vacuum therein, a mechanism for intermittently cutting off communication between the suction nozzle and the vacuum chamber whereby the partial vacuum is greatly increased or the air pressure within the vacuum chamber is decreased intermittently or periodically whereby when the mechanism reestablishes communication between the vacuum chamber and the suction nozzle an increased suction draft is created in the said nozzle.

As a still further object the invention comprehends an improvement in vacuum cleaners which does not materially increase the cost of production, which is extremely simple in its construction, and which is highly efficient in its purpose.

With the above recited and other objects in view, the invention resides in the novel construction set forth in the following specification, particularly pointed out in the ap-

pended claims and illustrated in the accompanying drawings, it being understood that the right is reserved to embodiments other than those actually illustrated herein to the full extent indicated by the general meaning of the terms in which the claims are expressed.

In the drawings—

Figure 1 is a partial longitudinal sectional view through a vacuum cleaner constructed in accordance with the invention, said section being taken approximately on the line indicated at 1—1 in Fig. 2.

Fig. 2 is a transverse sectional view taken approximately on the line indicated at 2—2 in Fig. 1.

Referring to the drawings by characters of reference, 10 designates the suction nozzle of a vacuum cleaner having an intake mouth 11 and a discharge mouth 12 which extends into and communicates with a vacuum chamber or compartment 13 defined by a housing 14. A suitable fan or other air expelling means 15 is mounted on and secured to a drive shaft 16 which is connected with a motor, not shown, but contained in a motor housing 17. When the fan 15 is rotated, it operates to create a partial vacuum in the vacuum chamber 13 whereby a suction draft is created in the nozzle 10 to draw the dust, dirt or other foreign matter through the intake mouth 11 from the surface over which the nozzle is moved.

The improved means which constitutes the invention consists of a shutter 18 which is preferably mounted within the housing 14 in juxtaposition to the outlet end 12 of the suction nozzle and which is operatively connected with the motor shaft 16 for intermittently or periodically closing or cutting off communication between the suction nozzle and the vacuum chamber 13. As specifically illustrated, the shutter 18 is of circular or disk-like formation and is provided with an arcuate opening 19, said shutter being mounted on a shaft 20 and provided with peripheral gear teeth 21 which mesh with the teeth of a pinion 22 mounted on a counter shaft 23. The counter shaft 23 has secured thereto a pulley 24 and the motor shaft 16 has secured thereto a pulley 25 around which pulleys a belt 26 is trained whereby the counter shaft is driven from the motor shaft coincidentally with the driving of the fan 15. As the shutter 18 registers

with the discharge end 12 of the nozzle, communication is cut off between the vacuum chamber 13 and the suction nozzle 10 and it will, of course, be appreciated that the expulsion of air from the chamber while the shutter is in closed relation, tends to build up or increase a partial vacuum or in other words decrease the air pressure so that when the opening 19 of the shutter registers with the discharge end of the nozzle an increased suction draft is created in the nozzle. This serves to intermittently or periodically subject the surface being cleaned to puffs of suction draft whereby the cleaning action is more effective than where the suction draft is steady or continuous.

It is, of course, understood that the particular means shown for periodically interrupting the suction draft through the suction nozzle is merely illustrative of one means which may be employed and that no restriction or limitation is intended by the mechanism thus shown.

25 I claim:

1. In a vacuum cleaner including a suction nozzle, a chamber communicating with the nozzle and having means therein for creating a suction draft through the nozzle, and mechanism co-operating with the point of communication between the nozzle and chamber, said mechanism being positively driven by the suction draft-creating means for periodically and completely cutting off communication between the nozzle and said chamber, whereby to subject the surface be-

ing cleaned to a succession of suction impulses.

2. In a vacuum cleaner including a fan chamber, a fan in said chamber, a suction nozzle connected thereto and communicating therewith, and means for operating the fan to produce a suction draft through the fan chamber and nozzle, of mechanism for periodically cutting off and establishing communication between the fan chamber and suction nozzle for subjecting the surface being cleaned to a succession of suction impulses, said mechanism comprising a shutter member mounted in the fan chamber and extending over the point of communication of the suction nozzle therewith, said shutter member having an eccentric opening therein and operative means of connection between the fan operating means and shutter for rotating the same.

3. In a vacuum cleaner, a fan chamber, a fan therein for expelling the air therefrom, a suction nozzle having an intake mouth at one end and communicating at its opposite end with the fan chamber, mechanism for intermittently closing said latter communicating end whereby to periodically interrupt the suction draft through the intake mouth of the suction nozzle and whereby to periodically increase the partial vacuum in said fan chamber when communication is cut off between the suction nozzle and fan chamber, and a common means for driving the fan and said mechanism.

MILTON GOODMAN.
